PLASTIC DOILY

Richard F. Fricke, Leominster, Mass., assignor to Plasti-craft of Leominster, Inc., Leominster, Mass., a corporation of Massachusetts

Filed Feb. 4, 1960, Ser. No. 59,269

Term of patent 7 years

(Cl. D92—26)

The figure is a plan view of a plastic doily showing my new design.

The doily is of conventional thickness.

I claim:

The ornamental design for a plastic doily, as shown and described.
